CARRIER FOR CARTONS AND THE LIKE

Filed Jan. 17, 1949

UNITED STATES PATENT OFFICE

2,590,999

CARRIER FOR CARTONS AND THE LIKE

Vandel L. Nielsen, Greenville, Mich.

Application January 17, 1949, Serial No. 71,280

9 Claims. (Cl. 224—45)

1

My invention relates to devices for manually carrying a plurality of articles which are awkward, unwieldy, messy and unsanitary to carry without mechanical assistance. Devices embodying my invention are especially designed and adapted for the carrying of such articles as ice cream cartons and cans, but may, of course, be employed for carrying a wide variety of other articles.

I have devised a carrier which is simple in construction, inexpensive to produce and, at the same time, rugged, convenient and generally satisfactory for the purposes in mind.

My invention will be best understood by referring to the appended drawings forming part of this specification, wherein:

Fig. 1 is an elevational view, with a part cut away for added clearness, showing a preferred embodiment of my invention, with the manipulating parts in inoperative position;

Fig. 2 is a plan-section taken substantially along the line 2—2 of Fig. 1;

Fig. 3 is an elevation in a plane at right angles to that of Fig. 1, also with parts cut away;

Fig. 4 is a fragmentary elevational view of the manipulating parts of the device shown in Fig. 1 but in operative condition; and

Fig. 5 is a sectional view taken substantially along the line 5—5 of Fig. 1.

The numeral 10 indicates a cradle for supporting articles to be carried, such as a plurality of ice cream cartons or cans. This cradle 10 comprises a pair of similar members, preferably bar stock or tubular, secured as by welding or the like to a central post 12, preferably tubular. Other suitable material may be used.

Each of the cradle members comprises an element 15 which is roughly of triangular formation, having a pair of arms 16, 16 extending angularly from each other and in a plane perpendicular to the post 12 normally lying in a substantially horizontal plane. The arms 16 may conveniently diverge at an angle of about 45° from each other and terminate in integral arcuate end portion 18. The end portion 18 may conveniently extend upwardly and outwardly from the horizontal arms 16 at an angle of approximately 135° therefrom, and while shown as a substantially circular arc, it will be obvious that the end portions 18 may be of other suitable formation so long as they provide a satisfactory support for the articles being carried, so as to brace them against toppling over.

The post 12 is preferably of such a height that the manipulating portion attached thereto

2

and described hereinafter may be at a convenient level to be grasped by a man's hand, so that the device, when loaded and carried with the arm downwardly extended, will clear the ground by several inches.

Pivots secured adjacent the upper end of the post 12, as by means of a bolt and nut 22, is a pair of toggle levers 23, 23. These levers are formed of relatively stiff bar stock and are twisted 90° intermediate their ends, as seen best in Figs. 1 and 4, so that the upper portions 24 thereof lie in a vertical plane while the lower portions are perpendicular thereto, the latter terminating in arcuate finger portions 25. The upper extremities 24 of the bars 23 are pivotally connected to links 27, 27, the latter in turn being pivotally connected to a bar 30 which extends through a tubular handle portion 32.

Thus, it will be seen that the elements 23, 27 and 32 form a convenient and powerful toggle arrangement which operates as follows.

The cradle 10 is loaded symmetrically either with one 5-gallon carton C on opposite sides of the center post 12 or with two 2½-gallon cartons 25 on each side thereof, said cartons C being indicated in dotted lines in the drawings and standing vertically on the cradle 10. (Other objects, of course, may be carried.) When it is desired to transport the carrier along with the goods supported thereby, one lifts the handle 32, whereby the toggle arms 23 are moved downwardly to the position shown in Fig. 4, the fingers 25 pressing upon the upper surface of the carton C and possibly pressing into the same, inasmuch as these cartons, although of relatively stiff cardboard or the like and filled with frozen material, will ordinarily yield sufficiently to permit the toggle arms to distort them slightly. Thus, the toggle arms tightly engage the articles supported by the cradle and may be moved and carried by lifting bodily clearing the ground a few inches. Obviously, the cartons or other articles carried by the device are immediately released upon letting go of the handle 32.

It will be seen that I have provided a device having many advantages. The device is especially convenient for the delivery of ice cream cartons and the like from a truck to a store where the goods are to be dispensed. Ordinarily the trucker is required to carry such material in his arm or on his shoulder, and frequently sets it on the ground, which practice is not only inconvenient but results in inadvertently soiling the worker's clothes and the cartons themselves. By

the use of my improved device, the deliveryman may conveniently carry such articles without spoiling the appearance of his clothes or the cartons, and, at the same time, has one arm free for the opening and closing of doors, etc. Thus, use of my invention produces more sanitary conditions in the handling of foodstuffs.

While I have shown a preferred embodiment of my invention and certain preferred uses thereof, it will be readily understood that various modifications coming within the spirit of my invention and other applications thereof may readily suggest themselves to those skilled in the art. Hence, I do not wish to be limited except to the extent indicated in the appended claims.

I claim:

1. A carrier of the class described comprising a vertical member, a cradle carried at the lower portion thereof, and toggle lever means connected pivotally to the upper portion of said vertical member for manually carrying articles supported on said cradle, said toggle lever means comprising members engageable with downward pressure on said articles when upward force is applied to said means.

2. A carrier as defined in claim 1 wherein the cradle comprises a pair of similar skeletal members extending oppositely from said vertical member.

3. A carrier as defined in claim 1 wherein the cradle comprises a pair of similar frame members each forming a base and lateral support for the articles to be carried.

4. A device as defined in claim 3 wherein each member of the cradle is approximately triangular, having a pair of legs secured to the vertical member and extending substantially horizontally therefrom and thence upwardly and outwardly to form a lateral brace for articles to be carried.

5. A carrier as defined in claim 1 wherein the toggle lever means comprises a handle and a pair of crossed members pivoted together at their

crossing and to said vertical member, said crossed members being engageable with the top surface of articles to be carried for retaining the latter when the handle is lifted.

6. A carrier as defined in claim 5 wherein said toggle members comprise downwardly convex fingers.

7. A carrier as defined in claim 1 wherein the toggle lever means comprises a pair of crossed levers pivotally secured at their crossing to each other and to said vertical member, a substantially horizontal handle member, and a pair of links connecting the ends of said handle member to the upper ends of said crossed levers.

8. A carrier as defined in claim 1 wherein the cradle comprises a pair of substantially similar triangular members formed of drawn material.

9. A carrier of the class described comprising a post, an article supporting cradle secured to the base of the post, and tonglike means pivoted to the upper portion of the post, said tonglike means providing a carrier handle, crossed and pivotally connected levers for engaging articles supported on the cradle when the handle is lifted, and links connecting the handle and levers.
